UNITED STATES PATENT OFFICE.

THOMAS E. CLARK, JAMES E. CLARK, AND WILLIAM L. COOP, OF DETROIT, MICHIGAN,
ASSIGNORS TO CONTINUOUS TRAIN CONTROL CORPORATION, OF DETROIT, MICHIGAN, A CORPORATION OF MICHIGAN.

TRAIN-CONTROL SYSTEM.

Application filed November 15, 1926. Serial No. 148,406.

This invention relates to train control systems for railway trains traveling tracks divided into blocks, whereby one or both of two radio-frequency currents may be im-

5 pressed upon the track rails at spaced stations in order that electro-magnetic force or flux may be picked up from adjacent the rails by receiving coils in the locomotive or other vehicle which is properly provided

10 with air brakes and controlling instrumentalities for such brakes, so that the operation of the vehicle may be governed by such radio-frequency currents, and its object is to provide transmission instrumentalities

15 which will impress current of predetermined radio-frequency upon the rails when the block in advance is unoccupied, which will impress a current of another when the block in advance is occupied, and which will im-

20 press both of such currents upon the rails of the last block of controlled track so that proper instrumentalities on the locomotive may respond thereto and render the automatic brake-control mechanism inoperative.

25 A further object of this invention is to divide each block into cut-sections and to impress the same control current upon the sections of each block so that substantially the same electro-magnetic flux will be present along the entire length of such block.

This invention may be embodied in the construction illustrated in the accompanying drawings in which Fig. 1 is a diagram of a trackway installation adapted to impress 35 radio-frequency currents on the rails of the track. Fig. 2 is a diagram of installations designed to be connected to the last section of controlled trackway.

In the drawings, all the armatures are lettered *a* and *b*, and in the following description, these armatures will be designated by these letters together with the reference numerals of the relays to which each armature belongs.

40 The rails in the drawings are shown divided into cut-sections by insulation 3, preferably at points about one-half mile or 800 meters apart, and these points may be indicated by the half mile markers 4 and mile markers 5. Two cut-sections constitute a

50 block and a train control station is located at the exit end of each block. Both cut-sections of each block receive the same radio-fre-

quency current, the presence or absence of such current depending upon the occupancy 55 of that block and of the occupancy of the next block ahead.

The instrumentalities embodying the present invention are designed to impress a current of one predetermined wave length and 60 frequency upon the rails of a block when the block in advance is unoccupied and to impress a current of another shorter wave length and more rapid frequency upon such rails when the next block in advance is occupied. When a block is occupied, no effective current passes from the control instrumentalities at the entrance end thereof toward the exit end beyond the vehicle occupying the block, and another train entering 70 such block at its entrance end will detect no current in the rails. An open switch or broken rail has the same effect. The locomotives to be operated upon such controlled tracks are provided with means to pick up 75 induced electro-magnetic flux or force from the energized rails and to utilize such force to affect instrumentalities to control the operation of the air brakes and signals thereon, and any desired type of locomotive 80 installation may be employed.

Fig. 1 diagrammatically illustrates a tract installation embodying the present invention and a transmission station of this character is connected to the rails at the exit end of 85 each block of controlled track, and the frequency of the current output of each station is controlled by current received over the wires 7 and 8 from the next station in advance. A track battery 9 is connected to 90 the rails 1 and 2 at the exit end of the entrance cut-section A and a track battery 10 is connected to the entrance end of the rails 11 and 12 of the other cut section B. Current from battery 9 normally energizes track 95 relay 14 (not shown) of the next installation in the rear while track relay 15 of the control installation of any block is energized by the battery 10 of that block. Each of these relays are short circuited when the cut-section to which it is connected is occupied.

The only movable parts of the installation shown in Fig. 1 are the armatures of the several relays and they are shown in the solid line positions which they assume when 100 cut-sections B and C are occupied. If sec-

tions A, B and C were unoccupied, these armatures would assume the positions indicated by dotted lines. If sections A and B were unoccupied, current from battery 10 5 would energize track relay 15 and its armatures *a*, *b* and *c* would be attracted. Current would flow from battery 9 next in the rear of station B to track relay 14 (not shown) of the next station in the rear and cause its 10 armatures *a* and *b* to close that end of the circuit to relay 17. Current would then flow from battery 18 of station B over wires 19 and 20, armature 15^a, wire 22, control relay 16, wire 7, armature 14^a of next station 15 in the rear, wire 23 at that station, relay 17, wire 24, armature 14^b, wire 8 to station B, armature 15^b and wire 25. This is the normal condition of the wayside circuit. When a locomotive enters cut-section A, it 20 short circuits relay 14 of the installation next in the rear and causes the circuit of wires 7 and 8 to be opened, resulting in relay 16 of station B to be de-energized and further resulting in the dropping of armature 25 16^a and in the closing of the supply circuit for the generator of high frequency currents at station B.

When the train leaves section A, the circuit of wires 7 and 8 closes behind it but 30 as it enters section B, it short circuits track relay 15 of station B which drops its armatures, thus opening the above described circuits so that control relay 16 cannot again be energized until the train leaves section 35 B. Relay 17 at any station is therefore de-energized so long as either of the next two cut-sections in advance are occupied; track relay 15 is de-energized so long as the cut-section to which it is connected is occupied; and control relay 16 is de-energized 40 so long as either of the cut-sections of the block in the rear is occupied.

A. C. current preferably of 110 volts, is supplied to the station from any suitable source by the line wire 27 ad justably connecting to the primary winding 36 of a transformer 28; and wire 29, armature *a* of relay 30 and line wire 31 connect the other end of this winding 36 to the current 45 source. Relay 30 receives current from the battery 18 over wires 19 and 32 and connects to the other side of the battery by wires 34 and 33, armature 16^a and wire 35, so that so long as control relay 16 is de-energized A. C. 50 current will flow to winding 36.

No current flows to the winding 36 of any station so long as the block to which the station belongs, is unoccupied, that is, so long as its control relay 16 is energized.

Each station embodies two electron tubes, the oscillations of the output tube 40 being controlled by those of the master tube 41. As the construction of these tubes is well known, the details need not be described.

The main transformer has three secondary

windings 42, 43 and 44, and the current for the filament of tube 40 travels the circuit of winding 42, connector 45 extending between the blocking condensers 46, winding 44 and wire 47, and back over wire 48. The current for the filament of tube 41 travels the right-end portion of winding 42, connector 45, left-end portion of winding 44, wire 49 and back over wire 50.

The plate current of tube 41 travels from 75 the filament of this tube to the plate and thence over wire 52 to a tap on winding 43, while the plate current of tube 40 travels from the filament of that tube to the plate and thence over wire 53 to the end of winding 43. Choke coils 54 are inserted in these wires 52 and 53 to block the radio-frequency oscillations and force them through the condensers 55 and 56 to be explained later on.

The oscillatory circuit which generates 85 the train control currents is governed by an inductance 57 and condensers 58 and 59, between which the wire 60 attaches and this wire extends to the connector 45. A grid leak 61 and choke 62 connect wire 60 to wire 63 which terminates in the grid of the tube 41, and also connect to one end of the inductance 57 and to the condenser 58. The other end of the inductance 57 and the condenser 59 connect to the wire 64 which 90 extends between the condenser 55 and a grid condenser 65 and thence through grid leak 66 to the grid of tube 40. It will thus be seen that the grid and plate of tube 41 are connected to the ends of the inductance 57 and condensers 58 and 59 whereby the tube 41 is caused to produce oscillations of a pre-determined frequency, this being governed 100 by the inductance 57 and the capacity of the condensers 58 and 59.

The plate output of tube 41 being impressed upon the grid of tube 40, the oscillations of tube 40 are governed thereby, and therefore the plate output of this tube 40 is always of the same frequency as that of tube 41, and this is unaffected by any connections or conductors which may be attached to the plate circuit of tube 40. The plate output of tube 40 passes through condenser 56 to primary 68 of the output transformer 69 and thence over wire 67 to wire 60 terminating in conductor 45. The grid of tube 40 is unloaded through a leak 70 and choke 71 connecting to wire 67. Practical tests have demonstrated the advisability of using a tube 40 of fifty watts rating and a tube 41 of seven and one-half watts rating.

The output transformer 69 has two secondary output windings 73 and 74, the former connecting to the rails 11 and 12 of cut-section B by means of wires 75 and 76 and the latter to rails 1 and 2 of cut-section A by means of wires 77 and 78. As the length of these wires 77 and 78 is the length 125

of cut-section B, the step-down transformer 79 may be connected into these wires adjacent the rails 1 and 2 so that high-potential current of low amperage may be received from secondary winding 74 and be re-transformed to low potential and greater amperage at cut-section A, thus permitting the use of small wayside wires.

As stated before, the transformer 69 becomes operative as soon as cut-section A is occupied and this continues until both sections A and B are cleared. As soon as cut-section B is occupied there is no necessity of impressing current on rails 1 and 2 of section A, and a relay 81 is therefore installed to open and close the circuit between the winding 74 and these rails, the circuit to this relay being from battery 18 over wires 19 and 20, armature 15^a, wire 82 to relay 81 and over wires 83 and 33, armature 16^a and wire 35 to the battery. The connection of wire 83 to wire 33 instead of to wire 35 directly is to avoid energizing relay 81 when section A is unoccupied.

In order to change the rate of the oscillating current and of the current impressed upon the rails so as to indicate that the next block in advance is unoccupied, a shunt circuit consisting of the wire 89 connecting to wire 64, the armature α of relay 86, and wire 90 connecting to a tap on inductance 57 is employed, the closing of this circuit shortening the inductance and therefore increasing the rate of oscillations of the output current. Relay 86 connects to wire 34 by wire 87 and to wire 20 by wire 88 and armature 17^a, so that so long as the block in advance is unoccupied and the adjacent relay 17 is energized, relay 86 will be energized and current of more rapid oscillations will result. But if the block in advance is occupied, relays 17 and 86 will be de-energized and current of less rapid oscillations will result, and when picked up by the locomotive through proper instrumentalities caution the engineman to reduce speed preparatory to stopping the train at the entrance of the next block.

Where a controlled trackway joins onto a trackway which is not provided with control stations, the rails of such trackways may be separated by insulation 3 and provisions may be made to simultaneously impress both of the above described radio-frequency currents on the rails of the track section next preceding the non-controlled trackway, in order that the two currents will so influence instrumentalities on the locomotive that non-controlled trackway ahead will be indicated. In order to bring the cost of such trackway installations down as low as possible it is advisable to employ two duplicates, as far as may be, of the standard installations shown in Fig. 1. In Fig. 2, the unnecessary parts of installation B are indicated by dotted lines or omitted. In installation C the relay 86

is either not provided with feed wires or is omitted so that the circuit between wires 89 and 90 is always open and the full length of inductance 57 is always employed. In installation D, armature α of relay 86 is permanently held up by a pin 92 so that only a portion of inductance 57 is utilized, this resulting in higher frequency oscillations in the secondary winding 73 of installation D while lower frequency oscillations occur in winding 73 of installation C. The supply wires 27^a and 31^a for the main transformer of installation D connect to the wires 27 and 29 of installation C, the connection between wires 31^a and 29^a again being permanent as one relay 30 at station C is sufficient.

A battery 94 connects to the track rails 1 and 2 of section C by means of wires 95 and 96, 82^a and 83^a, and normally energizes relay 14 at station B so that until section C is occupied relay 16 at installation C is energized by current passing from its battery over wire 8, armature 14^b at station B, wire 24, relay 17, wire 23, armature 14^a, wire 7, relay 16 of installation C, and wires 22 and 19. Energized relay 16 holds up its armature α and holds open the circuit of relay 30 until section C is occupied and the installations C and D are inoperative. But as soon as section C is occupied relay 14 at station B is short circuited resulting in the circuit to relay 16 at installation C being opened and its armature α dropping to close the circuit to relay 30. Both installations C and D will now become operative to impress both of the two radio-frequency currents of different wave lengths on the rails of section C.

It will be observed that these installations are all biased on the side of safety, that is, the breakage or disconnection of any wire or of any tube or other device employed will result in the interruption of radio-frequency current which will result in the same lack of such current in the rails as occurs when the block being entered is already occupied.

The cut-sections A and B may be of any other desired length and the strength of the batteries 9 and 10 will be proportioned accordingly, as will also the several transformers and electron tubes, but such changes as well as changes in the details of construction are well within the province of radio engineers.

We claim:—

1. In a train control system, the combination of a trackway divided into blocks, each comprising a plurality of sections, a radio-frequency current generator at the exit end of one block embodying an output winding for each track section of said block, wires connecting said output winding to the exit end of the rails of each section, a track battery connected to one end and a track relay connected to the opposite end of each track section, a control relay having an ar-

mature adapted to cause the closing of the supply circuit for said generator, a current source, a circuit between said current source and said control relay which circuit is controlled by said track relays.

2. In a train control system, the combination of a trackway divided into blocks, each comprising a plurality of sections, a radio-frequency current generator and embodying output windings connected to the exit ends of the several block sections, a control relay adapted to normally hold open the supply circuit for said generator, a current source for said relay, a track battery connected to one end and a track relay connected to the opposite end of each track section, and a circuit between said current source and said control relay adapted to be closed when either of said track relays is short-circuited.
- 15 3. A train control system comprising track rails divided into blocks and the blocks divided into sections, a generator for radio-frequency currents embodying an output transformer including a plurality of output windings, and wires connecting one of said windings to the rails of each block-section.

4. A train control system comprising track rails divided into blocks and the blocks divided into sections, a generator for radio-frequency currents embodying an output transformer including a plurality of output windings, and wires connecting one of said windings to the rails of each block-section and means whereby the occupancy of one block-section interrupts the passage of current to the section next in the rear.

5. A train control system comprising track rails divided into blocks and the blocks divided into sections, a generator for radio-frequency currents embodying an output transformer including a plurality of output windings, and wires connecting one of said windings to the rails of each block-section and means whereby the occupancy of the section at the entrance end of the block causes the transmission of radio-frequency

current to the rails of the several sections of said block.

6. A train control system comprising rails divided into blocks and the blocks divided into sections, means for impressing radio-frequency currents of two different frequencies upon the rails of one of the blocks embodying an output transformer including a plurality of output windings, wires connecting each of said windings to the rails of a block section, and means responding to the occupancy of the block next in advance to predetermine the frequency of such currents.

7. A train control system comprising track rails divided into adjacent controlled track and non-controlled sections, a generator of radio-frequency currents connected to the exit end of the controlled section, a plurality of generators of radio-frequency currents of different frequencies connected to the entrance end of the non-controlled section, means connected to each section for causing the instrumentalities connected thereto to function when such section is occupied, and means at the generator connected to the controlled section and controlled by the instrumentalities connected to the non-controlled section for selecting the frequencies of the current impressed upon the rails of the controlled section.

8. A train control system comprising track rails divided into blocks and the blocks divided into sections, a source of alternating current, means at each block for transforming said current into radio-frequency currents, means connected to a transforming means for one block to impress such currents on the block sections of said block independently of each other, and means responsive to the presence or absence of trains in the block ahead to determine the frequency of the currents thus impressed.
